UNITED STATES PATENT OFFICE.

EDWARD B. McCABE AND GUY C. CHAMBERLAIN, OF CARBONDALE, PENNSYLVANIA,
ASSIGNORS TO CARBONDALE MACHINE COMPANY, OF CARBONDALE, PENNSYLVANIA, A CORPORATION OF PENNSYLVANIA.

HEAT INTERCHANGER.

Application filed August 1, 1927. Serial No. 209,714.

This invention relates to heat interchangers of the type in which two fluids are caused to flow in contact with opposite surfaces of a dividing wall and preferable in opposite directions, whereby the temperature of one is lowered by the heating of the other. 5

The invention relates particularly to the type in which there is a bank of parallel tubes supported by tube sheets at opposite ends of a shell or casing. 10

One object of the invention is to facilitate the maintenance of tight joints during the expansion and contraction of the parts due to fluctuations through wide ranges in temperature. A further object of the invention is to so support the tube sheets that the heads of the shell may be removed without disturbing the joints at which the tube sheets are connected to the shell. 15

As one important feature of the present invention, the bank of parallel tubes are connected to separate tube sheets, one of which is of such diameter that it may slide longitudinally through the shell and be sealed to form a fluid tight joint at the far end of the shell independent of the securing means for shell heads. 20

A further important feature involves the provision of expansion joints in the shell so that the length of the shell may vary with changes in the length of the tube and strain on the joint thus obviated. 30

In the accompanying drawing there is illustrated one embodiment of the invention, and although various features of this preferred embodiment involve important minor features of the invention, yet we do not desire to be limited to the specific construction illustrated as various changes may be made within the scope of the invention as defined 35 in the appended claims. 40

In the accompanying drawing, the view is a central longitudinal section through a heat interchanger construction in accordance with our invention. 45

In the construction illustrated, there is provided a shell or tubular casing 10 formed of sheet metal or any other suitable material and having an inlet 11 and an outlet 50 12 adjacent to opposite ends thereof and preferably at opposite sides. Within the shell are a plurality of tubes 13 extending lengthwise thereof through which one fluid

is to be delivered and out of contact with the fluid which is circulated through the 55 shell outside of these tubes.

These tubes are connected to tube sheets 14 and 15 in any suitable manner so as to form fluid tight joints. The particular manner for connecting the tubes to the tube 60 sheets is not important as they may be threaded in place, expanded in the apertures of the tube sheets or provided with gaskets or other sealing means.

As one important feature of the invention, 65 the tube sheet 14 is made of a diameter slightly less than that of the shell so that the tubes connected to this tube sheet may be projected lengthwise through the shell into position. 70

The shell is provided with an annular 75 collar 16 which has an inwardly extending flange portion provided with a seat 17 within the shell and with which the tube sheet 14 may engage. Any suitable sealing means, such for instance as a gasket, may be disposed between the tube sheet and the seat. 80

At the opposite end of the shell suitable means are provided for forming a fluid 85 tight joint between the tube sheet 15 and the shell. 90

As shown the shell has a collar 18 which does not project inwardly beyond the inner surface of the shell so that it does not interfere with movement of the tube sheet 14 through the collar or flange 18. 95

The tube sheet 15 is made of substantially the same outside diameter as the flange or collar 18 so that the two may be 100 connected together by bolts 19 or in any other suitable manner and the joint between the two sealed by a gasket engaging a seat 20 on the outer surface of the collar 18.

For firmly holding the tube sheet 14 against the collar 17, there are provided bolts 21 which may extend through the collar 16 inside of the seat 17 or may extend through an annular clamping ring 22 seating on the outer side of the collar 16, that is, on the side opposite to the tube sheet 14 so that upon tightening the bolts 21, the inwardly extending flange of the collar 16 may be clamped between the tube sheet 14 and the clamping ring 22. 105

The shell may be provided with any suit-

able form of outer heads for delivering liquid and receiving it from the tubes 13.

As shown a substantially dome shaped head 23 having a central inlet passage 24 is clamped to the collar 16 by means of bolts 25 and the joint between the head and collar is sealed by a gasket 26.

At the opposite end there is a second dome shaped head 27 having an outlet 28 and 10 having a flange which may be secured to the flange 18 by the same bolts 19 that hold the tube sheet 15 in place. Between the head 27 and the tube sheet 15, there is provided a suitable sealing gasket 29.

15 As the tubes are fixed to the tube sheets 14 and 15 and as the latter are clamped to the ends of the shell, it will be apparent that a relative expansion of the tubes and shell would create strain tending to loosen the 20 joints.

To avoid this, there are provided one or 25 more expansion joints 30 which are preferably in the form of annular U-shaped flexible sheet metal sections having their opposite sides connected to spaced sections of the shell. Two of these joints are shown, one adjacent to the outlet end of the shell and the other adjacent to the inlet end of the shell, although in some constructions 30 only one such joint need be employed.

The opposite edges of the joint member are preferably welded to the shell so as to form a permanent connection thereto and also the inlet and outlet conduits 11 and 35 12 are welded to the shell and the collars or flanges 16 and 18 are likewise welded in place.

When it is desired to clean the apparatus, 40 the outer heads 23 and 27 may be removed, if it is necessary to clean only the interior 45 of the tubes. If it is desired to clean the interior of the shell and the exterior of the tubes, the bolts 21 and 19 may be removed and the entire bank of tubes may be slid endwise out of the shell without disturbing the joints between the tubes and the tube sheets 14 and 15.

Although our improved heat interchanger 50 may be used for the treatment of various kinds of fluids, the form illustrated is designed particularly for use in oil refinery practice.

Having thus described our invention, what 55 we claim is new and desire to secure by Letters Patent is:

1. A heat interchanger, including a shell 60 having a collar at one end presenting inwardly and outwardly extending flanges, a tube sheet of smaller diameter than said shell and slidable therethrough into engagement with said inwardly extending flange, a clamping ring at the outer side of said last mentioned flange, means for securing together said clamping ring and said tube sheet on opposite sides of said inwardly ex-

tending flange, a second tube sheet at the opposite end of the shell, and means for detachably securing it to the end of the shell.

2. A heat interchanger including a shell 70 having collars at opposite ends, one having inwardly and outwardly projecting flanges and the other having an outwardly projecting flange, a plurality of tubes within said shell and having tube sheets at opposite ends, one of said tube sheets being adapted 75 to seat against the inner surface of said inwardly projecting flange and the other against the outer surface of the outwardly projecting flange of the second mentioned collar, a pair of heads for said shell, one 80 being detachably secured to the first mentioned collar and the other being detachably secured to the second mentioned tube sheet, means for securing the first mentioned tube sheet to the first mentioned collar, and 85 means for securing the second mentioned tube sheet to the second mentioned collar, whereby said heads may be removed without disturbing the relationship of the tube sheets to the collars, and whereby the tubes 90 and tube sheets may be removed as a unit from the shell.

3. A heat interchanger including a shell, 95 a plurality of tubes disposed therein, separate tube sheets at the ends of said tubes and separate heads at the ends of said shell, said shell at one end having inwardly and outwardly extending flanges with the adjacent tube sheet seating against the inner surface of the inwardly extending flange and the adjacent head being secured to the outwardly extending flange independently of said tube sheet, and said shell at the opposite end having an outwardly extending flange with the adjacent tube sheet seating 100 upon the outer surface thereof and the adjacent head seating upon the outer surface of said tube sheet, means for securing said last mentioned tube sheet to said last mentioned flange, and independent means for 105 securing said last mentioned head.

4. A heat interchanger including a shell, 115 a plurality of tubes disposed therein, tube sheets at opposite ends of said tubes, means for detachably securing each tube sheet to its corresponding end of the shell to form fluid tight joints, a pair of heads at the outer sides of said tube sheets, and means independent of said first mentioned securing means for detachably securing said heads in position, whereby said heads may be removed without disturbing said fluid tight joints.

5. A heat interchanger including a shell 125 having inwardly and outwardly extending flanges at one end thereof, a tube sheet of smaller diameter than said shell and slid- 130 able therethrough into engagement with said inwardly extending flange, a clamping ring at the outer side of said last mentioned

flange, means for securing together said clamping ring and said tube sheet to clamp said flange therebetween, a head secured to said outwardly extending flange independent of said tube sheet and said clamping ring, a tube sheet at the opposite end of said shell and detachably secured to the latter, and a head detachably secured to the outer side of said last mentioned tube sheet.

Signed at Carbondale, in the county of 10
Lackawanna, and State of Penna., this 25th
day of July, 1927.
